UNITED STATES PATENT OFFICE.

VICTOR EMIL EMGARTH, OF PHILADELPHIA, PENNSYLVANIA.

ROTARY RECIPROCATING PUMPING APPARATUS.

SPECIFICATION forming part of Letters Patent No. 660,681, dated October 30, 1900.

Application filed July 25, 1899. Serial No. 726,048. (No model.)

To all whom it may concern:

Be it known that I, VICTOR EMIL EMGARTH, a citizen of the United States, residing at the city of Philadelphia, in the county of Philadelphia and State of Pennsylvania, have invented certain new and useful Improvements 5 in Rotary Reciprocating Pumping Apparatus, of which the following is a specification.

My invention has relation to a rotary reciprocating pumping apparatus, and in such connection it relates to the particular construction and arrangement of such an apparatus.

The nature and scope of my invention will 15 be more fully understood from the following description, taken in connection with the accompanying drawings, forming part hereof, in which—

Figure 1 is a view, partly in side elevation 20 and partly in broken section, of a rotary reciprocating pumping apparatus embodying the features of my invention. Fig. 2 is a top or plan view of the pumping apparatus, partly sectioned. Fig. 3 is a vertical sectional view 25 on the line xx of Fig. 1. Fig. 4 is a diagrammatic view illustrating the periphery of the sleeve or collar of the plunger, projected upon a flat surface to more clearly illustrate the cam projection thereof; and Fig. 5 is a side 30 elevational view, in broken section, of a modified form of the plunger with a cam-groove provided with dwell and thrust portions.

Referring to the drawings, a and a' represent hollow standards united to each other at 35 the top and bottom by hollow casings a^2 and a^3 of oblong cross-section and forming, respectively, the inlet and outlet chambers for fluid. These oblong casings are provided with an inlet a^4 and with an outlet a^5 , and the 40 standards a and a' are provided with inlet and outlet ports a^6 and a^7 , leading to the cylinders b and b' , through openings c^2 in valves c and c' in the ends of said cylinders, to be presently fully explained. The direction of 45 travel of the fluid from the inlet to the outlet of the apparatus is indicated by the arrows in Fig. 1 of the drawings. The two cylinders b and b' are supported in horizontal position by the standards a and a' and are 50 provided with glands or stuffing-boxes b^2 and b^3 . The valves c and c' are cup shape and perforated and abut against one end of each of the said cylinders, as illustrated in Fig. 1, and are respectively secured to a horizontal

shaft d . This shaft is journaled at each end 55 in brackets or bearings d' and d^2 , provided with glands or stuffing-boxes d^3 and d^4 . Between the outer wall of each valve and the end bearings of the shaft d in the latter is provided a recess or way d^6 , and in the wall 60 of each valve are provided openings d^7 , so that fluid from the respective cylinders may enter said openings d^7 into the recess or way d^6 to form lubricating or antifriction-fluid packings between the valves c and c' and 65 bearings d' and d^2 of the shaft d , and also to effect a counter-balancing influence of the valves with respect to the bearings of the said shaft d during the forward reciprocation of the plunger, thereby to insure within either 70 cylinder b or b' a reliable balance-valve for the working parts of the pump. On one end of the shaft d is mounted a pulley d^8 for rotating said shaft. On the shaft d are provided splines or ribs d^9 , adapted to secure the 75 plunger e against turning independently of the shaft d , but not to prevent the sliding of the same back and forth on said shaft d . The plunger e in Figs. 1, 2, and 3 is provided with a collar or sleeve e' , having a cam 80 projection e^2 , with two oppositely-arranged thrust portions e^3 and e^4 and two dwell portions e^5 and e^6 , interposed between the said thrust portions, as illustrated in Figs. 2 and 4.

g and g' are two rolls fixed to the casing a^3 85 and arranged to engage the cam projection e^2 of the collar or sleeve e' of the plunger e to permit of the reciprocations of the plunger in the respective cylinders b and b' and also to hold momentarily the plunger during the 90 alternate opening and closing of the openings c^2 of the cup-shaped valves c and c' to and from the cylinders b and b' and to and from the inlets and outlets a^6 and a^7 of the casings a and a' and anterior to further reciprocations 95 of the plunger on its shaft d .

In Fig. 5 is illustrated a modification of the plunger e , which in this instance is provided with a cam-groove e^7 , with two oppositely-arranged thrust portions e^8 and two dwell portions e^9 , interposed between the thrust portions in a similar manner as is illustrated for the cam projections e^2 of the plunger e in Figs. 1, 2, and 3, and particularly in Fig. 4. In this instance but one roll e^{10} is employed, arranged horizontally and journaled to the casing a^3 . The roll e^{10} , being fixed, has a bearing within the cam-groove e^7 , and in the ro-

tation of the plunger *e* with the shaft *d* it is given thereby a reciprocatory movement on the said splined shaft *d*, and likewise is afforded a momentary dwell to permit of the alternate opening and closing of the inlets and outlets *c*² of and from the valves *c* and *c'* to the cylinders *b* and *b'*, with the inlets and outlets *a*⁶ and *a*⁷ of the casings *a* and *a'* anterior to the further reciprocation of the plunger *e* on the shaft *d*.

The mode of operation of the pumping apparatus hereinbefore explained is as follows: When the plunger, for example, as illustrated in Fig. 1, is near the end of the cylinder *b'*, the valve *c'* and the rolls *g* and *g'* will have moved the plungers *e* so as to engage about the middle of the dwell portion *e*⁶ of the cam projection *e*², as illustrated in Figs. 1 and 2. In this position the two valves *c* and *c'* will be turned by the shaft *d* to completely close the opening *a*⁶, leading to the cylinder *b* from the hollow standards *a*. The two valves *c* and *c'* are so arranged on the shaft *d* that their openings *c*² are opposite to each other. The further rotation of the shaft *d* now turns the plunger *e* without moving it longitudinally until the rolls *g* and *g'*, Figs. 1 and 2, are about to be brought into engagement with the thrust portion *e*³ of the cam projection *e*². If the plunger *e* is to be forced longitudinally to the right by the thrust *e*⁴, then during the movement of the plunger to clear the rolls *g* and *g'* from the dwell portion *e*⁶ the two valves *c* and *c'* present, at the instant the plunger moves to the right, a small portion of the opening *c*² of the valve *c'* to the outlet-opening *a*⁷ of the standard *a'* and a small portion *c*² of the valve *c* to the inlet-opening *a*⁶ from the standard *a*, as illustrated in Figs. 1, 2, and 3, thus partially opening the water-inlet *a*⁶ of the standard *a* and the water-outlet *a*⁷ from the standard *a'*. As the plunger *e* continues to move longitudinally, as well as in a rotary direction, the valves *c* and *c'* will continue to rotate until at a point when the plunger *e* is midway between the ends of the respective cylinders *b* and *b'* and the rolls *g* and *g'* are at the middle of the thrust portion *e*³, when the openings *c*² in the valves *c* and *c'* will be at their widest extent and begin to decrease as the plunger *e* travels toward the right-hand end of the cylinder *b'*. When the rolls are brought to a position corresponding to the center of the second dwell *e*⁵ of the cam projection *e*², the plunger *e* will be adjacent to the right-hand end of the cylinder *b'* and the inlet *a*⁶ and outlet *a*⁷ will both be completely closed. The further movement of the shaft *d* causes merely a rotary movement of the plunger *e* and also turns the valves *c* and *c'*, so as to present at the moment the rolls *g* and *g'* are brought into engagement with the thrust portion *e*⁴ and the plunger *e* begins to travel to the left the openings *c*² to open, respectively, the inlet *a*⁶ and outlet *a*⁷ of the standard *a*.

Having thus described the nature and objects of my invention, what I claim as new, and desire to secure by Letters Patent, is—

1. In a rotary reciprocating pumping apparatus, two hollow standards united to each other by hollow casings provided with an inlet and an outlet registering with an inlet-port and an outlet-port provided in said standards, a splined shaft provided with cup-shaped valves rotatable with said shaft and having openings in communication with one end of each of two fixed cylinders supported by said standards, each of said cylinders at one of their ends being provided with a gland or stuffing-box, a plunger secured to said shaft but free to rotate therewith and provided with a cam having two thrust and two dwell portions, the former adapted to permit of the reciprocations of said plunger in said cylinders and the latter adapted to hold momentarily said plunger during alternate opening and closing of the openings of said rotary valves in communication with one end of each of said cylinders and anterior to further reciprocations of said plunger on said shaft and roller means engaging said cam, substantially as and for the purposes described.

2. In a rotary reciprocating pumping apparatus, two hollow standards united to each other by hollow casings provided with an inlet and with an outlet registering with an inlet-port and an outlet-port provided in said standards, a splined shaft provided with cup-shaped valves revolvable with said shaft and having openings in communication with one end of each of two fixed cylinders supported by said standards, each of said cylinders at one of their ends being provided with a gland or stuffing-box, said shaft journaled in end bearings and between said bearings and walls of said cup-shaped valves are provided recesses or ways and perforations in the walls of said valves to form a lubricating or anti-friction-fluid packing between said valves and end bearings for said shaft, a plunger secured to said shaft but free to rotate therewith and provided with a cam having two thrust and two dwell portions, the former adapted to permit of the reciprocations of said plunger in said cylinders and the latter adapted to hold momentarily said plunger during alternate opening and closing of the openings of said rotary valves in communication with one end of each of said cylinders and anterior to further reciprocations of said plunger on said shaft and roller means engaging said cam, substantially as described.

In testimony whereof I have hereunto set my signature in the presence of two subscribing witnesses.

VICTOR EMIL EMGARTH.
